CLAIM

I claim the ornamental design for the landscaping block, as shown and described.

DESCRIPTION

FIG. 1 is a top-front perspective view of a landscaping block.

FIG. 2 is a bottom-rear perspective view thereof.

FIG. 3 is a front view thereof.

FIG. 4 is a rear view thereof.

FIG. 5 is a first side view thereof.

FIG. 6 is a second side view thereof.

FIG. 7 is a top view thereof; and,

FIG. 8 is a bottom view thereof.

The broken lines in the drawings indicate portions of the landscaping block that form no part of the claimed design.
